DESIGN FOR A DRESS

Texie Tilton, Webster Groves, Mo.

Application April 5, 1944, Serial No. 113,147

Term of patent 3½ years

(Cl. D3—26)

To all whom it may concern:

Be it known that I, Texie Tilton, a citizen of the United States, residing in the city of Webster Groves, county of St. Louis, and State of Missouri, have invented a new, original, and ornamental Design for a Dress, of which the following is a specification, reference being had to the accompanying drawing, forming a part thereof.

In the drawing:

Fig. 1 is a front view of a dress, showing my new design, and

Fig. 2 is a rear view of the dress shown in Fig. 1.

I claim:

The ornamental design for a dress, as shown.

TEXIE TILTON.
